UNITED STATES PATENT OFFICE

1,938,748

WATER-TREATING APPARATUS

Charles Lee Hoge, Wichita Falls, Tex.

Application June 28, 1930. Serial No. 464,599

1 Claim. (Cl. 253—136)

This invention relates to apparatus for treating water and is adapted for use primarily in connection with railroad tanks.

It is an object of the invention to utilize the force of water being supplied to a tank or the like to operate an apparatus for treating the water after it reaches the tank, thereby obviating the necessity of utilizing other power for this purpose which is not always convenient or desirable, especially in out-of-the-way localities.

A further object is to provide a simple and efficient mechanism of this character which can be placed in position readily and can be utilized for metering the flow to the tank.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is an elevation of the complete apparatus.

Figure 2 is an elevation showing the opposite side of the rotor housing.

Figure 3 is a vertical section taken longitudinally through the stator and rotor.

Figure 4 is a section on line 4—4, Figure 2.

Figure 5 is a transverse section through the rotor.

Figure 6 is a transverse section through one head of the stator.

Figure 7 is a longitudinal section through the water nozzle.

Figure 8 is an end elevation thereof.

Referring to the figures by characters of reference, 1 and 2 designate the heads of a stator, the head 1 being provided with a central hollow extension 3 formed with a bearing 4 having a packing gland 5.

Head 2 is also provided with a central hollow extension 6 formed with a gear housing 7, and a combined bearing 8 and packing gland 9 is arranged on the housing.

Each of the heads 1 and 2 has an annular shoulder 10 from which is extended a flange 11 and the two flanges are connected by the rim portion 13 of the stator. A tubular extension 14 formed on the rim portion 13 constitutes the

inlet port of the stator and is tangent to the shoulders 10 or substantially so.

An elongated outlet port 15 is provided in the rim 13 and opens into the flared end of an overflow pipe 16 which is secured to or formed with the rim. This pipe tapers to its outlet end where it is adapted to be connected to a pipe 17 leading to the tank T to be supplied.

A conduit 18 is formed on rim 13 or can be secured thereto. One end thereof opens into the extension 14 while the other end is adapted to receive water from a pipe 19 to which it is supplied by gravity as shown or by a suitable forcing means. A cover plate 20 normally closes and seals the outer end of extension 14.

Bridging the outer sides of the heads 1 and 2 are brackets 21 which are secured to the flanges 11. These brackets have bearings 22 in which is journaled a shaft 23 also journaled in bearings 4 and 8 and extending through the extensions 3 and 6 and housing 7.

Secured to shaft 23 within extensions 3 and 6 is the hub 24 of a disk 25. This disk has a tight working fit between the heads 1 and 2 and is provided at its periphery with an annular channeled portion 26 having a tight working fit upon shoulders 10 and flanges 11. It also extends close to rim 13.

Arranged in the channeled portion 26 of the rotor are cups 27 preferably dished so that as they pass the inlet part the concave surfaces thereof will be positioned to receive the impact.

A nozzle 28 is screwed into extension 14 and has lugs 29 whereby it can be rotated readily by a suitable tool provided for that purpose. Access to the nozzle is obtained by removing plate 20. This nozzle is renewable at will and can be made of a material which will resist the action of the water.

A gear 30 is secured to shaft 23 and meshes with a gear 31 journaled at one side of the stator. This latter gear drives a pitman 32 which operates the pistons of a pump 33. A pipe 34 leads from the pump to the tank to which water is being supplied while another pipe 35 is used for supplying to the pump the treating liquid contained in a receptacle 36. A shaft 37 having agitating blades 38 is located in the receptacle 36 and is driven through gearing 39 from a shaft 40. This shaft can have a pulley 41 for receiving motion through a belt 42 from a pulley 43 on shaft 23.

Gearing indicated generally at 44 can be located in housing 7 for transmitting motion from 110

shaft 23 to the shaft 45 of a water meter indicated generally at 46.

It will be obvious that water flowing to a storage tank, such as used by railroads, will actuate 5 rotor 25 as it travels through the stator from the pipe 19 to pipe 17. This will cause the actuation of agitator 38, meter 46, and pump 33. Consequently the treating material in container 36 10 will be mixed thoroughly and then elevated by pump 33 to the storage tank where it will be discharged into the water delivered to the tank. The meter will also register the amount of water thus treated.

As before explained this apparatus is especially 15 useful in remote localities where power is not easily available for operating treating apparatus. It can be installed easily and the mere flow of water to the tank by gravity or otherwise will be sufficient to operate the several parts of the 20 mechanism.

What is claimed is:

In apparatus of the class described an overshot water motor for installation between alin-

ing horizontal inlet and outlet pipes, including a stator, a rotor therein, said stator having an elongated peripheral outlet of gradually increasing capacity along the bottom portion thereof opening into the outlet pipe, a peripheral conduit having a portion upon and concentric with the upper portion of the stator extending upwardly from the inlet pipe, said conduit being inclined downwardly toward the outlet pipe, an extension in communication with the lower end of said inclined portion of the conduit for directing a jet of water into the stator adjacent to but along a line extending away from the outlet, over the axis of the rotor, and substantially tangent to the rotor, said rotor having concave peripheral pockets for receiving the impact of the water jet, thereby to operate as an overshot rotor and travel oppositely to the direction of flow in the conduit, thereby to deliver the water from the nozzle over and around the rotor to and along the peripheral outlet and in the direction of the outlet pipe.
